US0D1005264S

(12) **United States Design Patent** (10) **Patent No.:** **US D1,005,264 S**
(45) **Date of Patent:** **** Nov. 21, 2023**

(54) **REMOTE CONTROL**

(71) Applicant: **Crestron Electronics, Inc.**, Rockleigh, NJ (US)

(72) Inventors: **Wendy Feldstein King**, Old Tappan, NJ (US); **Howie Balch**, Bloomingdale, NJ (US); **Sae Jhun**, Bayside, NY (US); **Daniel Previti**, Tappan, NY (US); **Douglas Jacobson**, Oradell, NJ (US)

(73) Assignee: **Crestron Electronics, Inc.**, Rockleigh, NJ (US)

(**) Term: **15 Years**

(21) Appl. No.: **29/802,461**

(22) Filed: **Aug. 5, 2021**

(51) LOC (14) Cl. **14-03**

(52) U.S. Cl.

USPC **D14/218**

CLAIM

The ornamental design for a remote control, as shown and described.

DESCRIPTION

FIG. 1 shows a top perspective view of a remote control according to a first embodiment.

FIG. 2 shows a bottom perspective view thereof.

FIG. 3 shows a top plan view thereof.

FIG. 4 shows a front view thereof.

FIG. 5 shows a rear view thereof.

FIG. 6 shows a left side view thereof.

FIG. 7 shows a right side view thereof.

FIG. 8 shows a bottom view thereof.

FIG. 9 shows a top perspective view of the remote control with alternate broken line portions.

FIG. 10 shows a top plan view thereof.

FIG. 11 shows a top perspective view of the remote control with alternate broken line portions; and,

FIG. 12 shows a top plan view thereof.

The broken lines showing portions of the remote control form no part of the claimed design.

1 Claim, 10 Drawing Sheets
